MATCH BOOK

Henry T. Roberts, Chicago, Ill.

Application August 1, 1938, Serial No. 222,458

2 Claims. (Cl. 40—2)

An object of my invention is to provide a usual type of match book which is modified in a simple and inexpensive manner to increase the appeal of the matches to the ultimate users thereof, such modification thereby acting as a business stimulator, especially from the standpoint of distributors using the match books as an advertising means.

A further object is to provide a match book with representations normally concealed from view and which can be viewed after certain seals are broken subsequent to the user acquiring the match book whereby match books having the characteristics of my invention are preferable to those of the ordinary type and thus the public acquires them more readily and thereby the advertising usually printed on or in the books is more readily brought to the view of the public.

Still a further object is to increase the appeal of the match books by including representations either on the matches themselves or within the cover of the book, the cover being sealed or some other means being provided to normally conceal the representations from view so that there is an element of chance as to what the representations are and thereby interest in the match book and opening it to determine what representations or combinations of representations there are in the books is stimulated.

More particularly it is my object to show such representations as "poker hands" either printed on the match splints or somewhere inside the match book, which representations are normally concealed from view so that two persons acquiring the match books can compare their relative "hands" after breaking the seals and thereby simulate a poker game or some other game depending upon the character of the representations.

Further objects are to provide sealing means for either the cover of the match book or to provide the cover unsealed and provide within the cover a sealing means for sealing the matches from view.

With these and other objects in view, my invention consists in the construction, arrangement and combination of the various parts of my match book, whereby the objects contemplated are attained, as hereinafter more fully set forth, pointed out in my claims, and illustrated in the accompanying drawing, in which:

Figure 1 is a perspective view of one embodiment of my invention showing a match book with the cover thereof sealed in closed position.

Figure 2 is a perspective view of the match book of Figure 1 showing it open and two of the splints removed.

Figure 3 is a perspective view of a modification in which a thin paper cover is provided for the match splints instead of sealing the main cover closed relative to the book.

Figure 4 is an enlarged end elevation of Figure 3 in the closed position.

Figure 5 is a perspective view of a construction somewhat modified from Figure 2 by having representations inside the cover instead of on the match splints.

Figure 6 is a perspective view of another modified structure in which the representations are on the inner face of an element which is secured by adhesive or the like to the outer face of the match book cover; and

Figure 7 is a perspective view of a modified cover in which a paper sack completely encloses the match splints instead of being over the front and back only thereof as in Figure 3.

On the accompanying drawing I have used the reference character C to indicate generally a cover for my match book and M the match splints therein. The match splints are perforated as at 11 to facilitate their detachability from the match book. The cover C has a bottom 10, a front flap 12, a back 13, a top 14 and a front 15. The front 15 has a tab 16 adapted to be secured against the flap 12 by the usual staple 17 which extends through the flap 12 and the back 13 and through the match splints for holding the cover C and the match splints assembled relative to each other. The front 15 is perforated at 18 whereby it may be readily separated from the flap 16 as in Figure 2, after which the flap (shown by dotted lines in this figure) can be removed so that it does not interfere with striking a match on the usual abrasive treated front face of the flap 12.

The match splints M as shown in Figure 2 are provided with representations 19 such as jacks, kings, spades, diamonds, etc., similar to playing cards so that when the match book is originally acquired, these representations which may simulate "poker hands" are hidden from view by the cover C retained as it is in closed or sealed position by the flap 16 and staple 17.

After the cover is opened, the poker hands are exposed to view and those held by one person can be compared with those held by another and a game thus played similar to poker so that interest in the matches is stimulated and thereby their distribution stimulated to increase their distribution for advertising purposes.

Instead of utilizing the cover C itself to cover and conceal the representations 18, cover means C' in the form of a sheet of paper may be provided as in Figure 3. The cover C' consists of a front wall 20, top wall 21 and back wall 22. The lower ends of the walls 20 and 22 as shown in Figure 4 may be retained in assembled position by the staple 17 and the front wall 18 of the cover C may have the flap 16 of Figure 1 eliminated and be tucked in behind the flap 12 in the usual manner. The cover C' may be of relatively thin paper as distinguished from cardboard for the cover C.

As shown in Figure 5, in order to reduce the cost of manufacture, the printing of the representations indicated in this figure as 19a may be on the inside of the cover C. The representations are normally concealed from view when the cover is sealed in position and exposed only when the seal is broken.

In Figure 6 I illustrate how the representations indicated at 19b may be placed on the back face of an element 23, such as a sheet of paper, which may be secured around its periphery by adhesive to the cover C. Perforations at 24 and a tab at 25 facilitate removal of the element 23 so that the representations can be observed. Normally however the representations are concealed as long as the element 23 remains in its initially applied position on the match book. This form of the invention is readily applicable to existing types of match books and so is the form shown in Figure 5.

In Figure 7 I illustrate a paper sack or the like 26 which is placed over the match splints and secured in position similar to the cover C' in Figure 3. The sack 26 in addition to covering the front and back of the match splints as in Figure 4 covers the sides and thus completely encloses the splints. The sack or the cover C' can be readily torn from position, one corner thereof being illustrated as being so torn in Figure 3.

Some changes may be made in the construction and arrangement of the parts of my match books without departing from the real spirit and purpose of my invention. I therefore intend to cover by my claims any modified forms of structure or use of mechanical equivalents, which may be reasonably included within their scope.

I claim as my invention:

1. In a match book, a cover, a plurality of match splints having bases, means for securing said bases in said cover with said cover extending down the front of said bases and across their bottoms, said match splints being detachable above their secured bases, said cover extending upwardly along the backs of the match splints, across the upper ends thereof and having a cover flap extending downwardly in front of the match splints, said cover flap having a marginal free end of reduced width secured by said securing means, for sealing said cover flap in position over said match splints, and representations on said match splints and concealed from view by said cover flap until it is broken from its marginal free edge and the cover flap opened, the portion of said cover extending down the front of said bases having abrasive with the abrasive exposed beyond the end of said marginal end of reduced width.

2. In a match book, a cover, a plurality of match splints therein, a staple for securing said match splints therein and means for sealing the free marginal edge of said cover in position over said match splints, said cover having a row of perforations separating said marginal edge from the body of the cover, said marginal edge being of less width than said cover, and representations on said match splints within said cover and concealed thereby from view until said body of said cover is separated from said marginal edge at said perforations.

HENRY T. ROBERTS.
